UNITED STATES PATENT OFFICE

HENRY O. LOEBELL, OF WHITESTONE, NEW YORK, ASSIGNOR TO HENRY L. DOHERTY,
OF NEW YORK, N. Y.

APPARATUS FOR MANUFACTURING COMBUSTIBLE GAS

Original application filed December 7, 1923, Serial No. 679,132. Divided and this application filed
October 12, 1926. Serial No. 141,047.

This invention relates to the manufacture of fuel gas, and more particularly to apparatus for making gas for industrial purposes by the complete gasification of coal.

5 The apparatus constituting the subject of this invention was originally described in my application, Ser. No. 679,132, filed December 7, 1923, of which this forms a divisional application.

10 The subject matter of the present case constitutes a modification and improvement in the apparatus shown and described in my co-pending application for the manufacture of fuel gas, Ser. No. 640,828, filed May 23, 1923, now matured into Patent 1,837,226, issued December 22, 1931.

15 The method of and apparatus for making fuel gas for industrial heating purposes described in the above application may be 20 briefly outlined as follows: The fuel to be gasified, preferably a mixture of coal and coke, is passed downwardly in a column through a shaft generator, and a high temperature zone is maintained in the mid portion 25 of the column by continuously blasting a mixture of preheated air and steam therethrough. The producer gas generated in the mid portion of the fuel column by the action of the hot blast mixtures is divided, and a 30 minor portion of this gas is passed up through the fuel column, heating and carbonizing the coal therein, and is withdrawn together with the products of distillation of the coal from the top of the column. A major portion 35 of the hot producer gas is removed separately from the generator through a central offtake which is suspended from the top of the shaft with its gas inlet adjacent the central axis of the high temperature zone.

40 The sensible heat in the gas removed is recovered in regenerators and returned by the blast gases to the fuel column.

A very considerable part of the carbonizing chamber of the apparatus used in carrying 45 out the process outlined above is occupied by the central gas offtake. Moreover, the path traveled by the blast gases through the fuel column is comparatively short in length, so that the high temperature gasifying zone 50 is limited in size. These features of the above

invention together with other features outlined in the method of operation, while of advantage in many ways, yet necessarily limit to a certain degree both the fuel handling and gas making capacity of the 55 apparatus.

The primary object of the present invention is to provide apparatus for making industrial gas by which a relatively larger volume of fuel can be economically and 60 efficiently gasified per unit of time than has been heretofore possible.

Accordingly one feature of the present invention contemplates the use of a circumferential offtake similar to the blast gas inlet 65 and vertically spaced therefrom. The blast inlet and gas offtake are provided with connections by which they are made interchangeable, and the nostrils through which air is introduced and exhaust gases are removed 70 are positioned on opposite sides of the shaft. These features combine to produce a greatly enlarged high temperature zone as well as an enlarged carbonizing zone, and thereby increases the fuel treating capacity of the 75 apparatus considerably.

Another object of the present invention is to provide apparatus for making industrial gas by use of which the fuel to be treated may be regularly and efficiently passed 80 through the gas generator and removed therefrom without obstruction or arching or the adhering of slag or coke to parts of the producer.

Other features of the present invention include an improved device for supporting fuel in a column and for removing fuel therefrom, and also a device for charging fuel into or discharging fuel from generators of the shaft type.

85 The combination of an open unobstructed gas generating shaft with a peripheral blast inlet and a device for removing coke and ash peripherally from the bottom of the column of fuel being treated are further features whereby clinkering of the charge is prevented, a variable rate of movement of fuel through the axial and peripheral portions of the shaft is effected, and an easily controlled 90 95 100

process and a uniformly gasified product are obtained.

With these and other objects and features in view, the invention consists in the improved gas making apparatus hereinafter described and particularly defined in the claims.

The various features of the invention are illustrated in the accompanying drawings, in which—

10 Fig. 1 is a view in vertical section with parts in elevation of a gas generator embodying the preferred form of the invention;

Fig. 2 is a top plan view partly in section of the generator shown in Fig. 1, taken on the line 2—2;

Fig. 3 is a horizontal sectional view of the generator taken on line 3—3 of Fig. 1;

Fig. 4 is a horizontal sectional view of the generator taken on the line 4—4 of Fig. 1;

20 Fig. 5 is a vertical sectional view illustrating the mechanism for charging coke and coal into the top of the generator;

Fig. 6 is a vertical elevation partly in section illustrating the coke and coal charging mechanism.

The manufacture of fuel gas may be carried out in the apparatus illustrated in the drawings substantially as follows:

Fuel to be carbonized is fed to a hopper 30 from a bin 12, and is intermittently introduced into the upper part of a gas generator shaft 14 by means of two rotary gas sealed charging devices 16, set in cast housings 18 directly above gate valves positioned 35 in two nostrils 20 of a charging bell or manifold 22. The fuel discharging from the manifold or bell 22 passes around a central gas off-take 23 and is distributed into the top of an upright column of fuel supported in the shaft 14. The upper portion of the fuel column or approximately the portion above a flat circumferential wall extension 24 in the shaft 14, comprises a carbonizing zone. The portion 40 of the fuel column below the wall extension 24 and extending downwardly a short distance below a flat circumferential wall extension 26 in the shaft 14, constitutes a blast or high temperature zone in which the fuel is maintained at a comparatively high temperature by partial combustion thereof. The portion 45 of the fuel column from the bottom of the blast zone to the bottom of the column is a cooling or quenching zone in which the unburned fuel and ash is cooled before being removed from the generator. Carbonized fuel and ashes are continuously discharged from the bottom of the column and fuel continuously moves downwardly 55 through the shaft.

The gas manufactured in the present apparatus may be a high grade industrial fuel gas similar to the gas described in my aforementioned application, Serial No. 640,828, 65 now Patent 1,837,926, and the same series of

reactions take place as in the case cited. In operating the present apparatus the air and steam used in making gas are preheated and then introduced into the blast zone of the fuel column to carry out the reactions outlined in the aforementioned patent. The mixture of air and steam is introduced into one of a pair of preheaters 28 which are so arranged that while one of the preheaters is used for preheating the gas and steam mixture, the other preheater is being heated by burning gas therein.

While some form of regenerator such as that shown may be used in preheating the blast gases, it is equally feasible and even advantageous in many instances to use a tile or high temperature metal recuperator for this purpose and the term preheater is used advisedly as broadly descriptive of the general type of apparatus used in effecting heat transfer.

When one preheater has been cooled to a fixed minimum temperature, the circulation of air and steam is changed to the other preheater which has been previously heated by the combustion of exhaust gases therein. The mixture of air and steam is introduced into the preheaters 28 through a pipe 30 in the top of exhaust sections 32 of the preheaters, passed downwardly through checker brick in these sections, then upwardly through checker brick in the main sections. In passing through the two sections of the preheater the mixture of steam and air becomes highly heated and it then flows through a nostril 34 into a circumferential passage surrounding the blast portion of the fuel column.

The circumferential wall extension 26, which constitutes an offset in the lining and shell of the generator, is placed directly above the inlet from the nostril 34. As the fuel in the column descends and passes this wall extension it can expand to fill the greater cross sectioned area in the shaft below the wall extension, and the outer face of this expanded section of the column will assume the angle of repose of the descending material. The space formed below the wall extension and between the face of the column of fuel and the generator lining, forming the passage 36, will always be of practically the same volume, and will extend around the whole circumference of the shaft. The nostril 34 is connected by a Y connection 38 to both of the preheaters 28, and hot valves 40 positioned in the connecting pipes permit the shutting off of either preheater while the other preheater is being used to heat the blast gases. A refractory baffle 42 of triangular cross section, (see Fig. 4), is set in front of the nostril 34 to deflect the gases entering through the nostril in both directions into the passage 36.

From the circumferential passage 36 the

mixture of steam and air in the blast enters the fuel column and combines with the carbon of the fuel according to the various reactions previously referred to, which are primarily exothermic and therefore maintain a high temperature zone in this portion of the fuel column. The producer gas formed in the high temperature zone passes upwardly through the expanded portion of the fuel column lying between the wall extensions 26 and 24, and a major portion of the hot lean gases are removed directly from this zone through a circumferential passage 44 below the flat wall extension 24, and are removed from the generator through a nostril 46. The blast inlet nostril 34 and the offtake nostril 46 are positioned on opposite sides of the shaft, so that the blast gases introduced through the nostril 34 are forced to follow a roughly diagonal upward course through the whole cross section of the fuel column in order to pass out through the nostril 46. The exothermic reaction between the blast gases and the fuel continues while the gas is traversing the distance between the two nostrils, or at least so long as there is any air or fuel unconsumed. Since the blast air is introduced into the column and the exhaust gases are removed from the column around its whole periphery and therefore are not limited except in a general way to a diagonal course through the column, it follows that practically all of the fuel column lying between the two circumferential wall extensions 24 and 26 is maintained at a high temperature. The enlarged area of the generator below the wall extension 24 permits an expansion of the fuel column in this high temperature zone, and thus increases the porosity of the fuel bed and insures a thorough penetration of the blast gases throughout the charge. The greatest concentration of ash and the highest temperatures will occur in the peripheral portion of the column adjacent the blast inlet. The fuel is passed through the shaft at such a rate that this concentration will not exceed a limit above which clinker trouble would occur, and for this reason quite a large proportion of fuel is allowed to pass the high temperature zone unconsumed. In case the temperatures adjacent the blast inlet get so high as to endanger the life of the refractory material forming the wall extension 26 and the generator lining, or in case the temperatures adjacent the gas offtake become too low, means are provided whereby the blast air and steam may be introduced through the nostril 46, and the blast gases may be removed through the nostril 34 after passing diagonally downward through the fuel column. The direction of the blast may be altered at will, but it is preferred to maintain an upward blast so far as possible.

The major portion of the exhaust blast

gases, which is removed through the offtake nostril 46, is generally passed through a Y connection 48 (Fig. 2) into one or both of a pair of waste heat steam boilers 50, although it may be carried directly to one of the pre-heaters 28 through conduits 52, (see Fig. 2). Hot valves 54 in the Y connection 48 and hot valves 56 in the conduits 52 control the direction of flow of the exhaust blast gases. These hot gases are preferably allowed to pass through one of the waste heat boilers, where they are cooled, and are then conducted through conduits 58 into the conduits 52 and thence into the preheaters 28 where they are burned. However, the cooled exhaust gases may be withdrawn through a main 60 to storage, where they can be used as a diluent for a richer coal gas removed from the top of the shaft. The waste heat boilers 50 are regular upright tubular steam boilers having water inlets 62 and steam connections 64 with the preheaters 28. These waste heat boilers will ordinarily produce enough steam to take care of the requirements of the gas making operation, but they may be supplemented with other steam generating equipment if necessary.

In order to supplement the exhaust blast gases from the generator, one or more stokers 66, adapted to burn coke breeze and waste fuels, are connected to the preheaters by conduits 68. These stokers are preferably of a standard type with a traveling grate, and are of sufficient capacity to maintain the preheaters at the high temperatures necessary for operation.

The volatile oils and other valuable by-products such as tars and ammonia are removed from the coal by low temperature carbonization. To accomplish this a minor portion of the producer gas being made in the blast zone is led upwardly past the circumferential offtake passage 44 through the carbonizing zone of the fuel column to distill off the by-products of the coal by a heat transfer therewith. This small amount of gas, cooled by its contact with the descending coal, and carrying with it the low temperature by-products, passes into the inverted cone central offtake 23 at the top of the shaft, and flows through a conduit 70 which conducts it to the usual purification and treating equipment. Thus the by-products may be removed by treating a comparatively small amount of gas, and the purified gas may be mixed with the gas passing through the outlet nostril 46 and waste heat boilers 50. By the time the fuel has moved downwardly through the carbonizing zone and reached the blast zone there is substantially no volatile material therein, and therefore the lean gas which passes out through the offtake nostril 46 contains substantially no by-products, and needs no special purification treatment. A large part of the minor portion of producer

gas which is passed upwardly through the carbonizing zone of the fuel column is generated in the peripheral sections of the blast zone adjacent the blast inlet, and by mounting 5 the rich gas offtake 23 axially in the top of the carbonizing chamber a uniform penetration of the heating gases throughout each cross-section of the upper carbonizing zone of the fuel bed is secured during the upward passage 10 of the gas from the peripheral sections of the blast zone to the axial offtake 23.

The column of fuel is supported in the bottom of the generator upon an eccentric cone platform 72 and a series of hopper-like receivers 74 in conjunction with radially placed horizontal platforms 76 positioned peripherally between the cone and the inner wall of the shaft. The cone is centrally supported on a bearing 78, and is revolved continuously 20 by means of a vertical shaft 80 which is connected by gears 82 to a drive shaft 84. The shaft 80 passes through a stuffing box in the bottom of the shell. The cone may be rotated in either direction and this rotation combined 25 with the eccentric mounting of the cone provides a means for agitating the central part of the fuel column. The weight of the column of fuel combines with the revolving action of the central cone to advance the fuel 30 in the lower part of the column toward the peripheral receiver openings, whence it falls onto the platforms 76. These platforms are reciprocated by means of water operated engines 86, discharging the coke and ash into 35 a hopper 88 in the bottom of the generator.

The cone discharging apparatus supporting the column of fuel in the shaft is designed and operated with the particular object of insuring so far as possible the uniform combustion of all sections of the charge during 40 its passage through the generator. It is apparent that in introducing the blast gases peripherally into the fuel column combustion will take place more rapidly in the peripheral 45 portions than in the axial portions of the column, because by the time the blast gases have penetrated to the center of the column they will have been stripped of a great proportion of their combustion supporting constituents. Thus in order to prevent clinkering 50 of the fuel in the outside sections, and at the same time to secure at least a partial combustion of the fuel in the center of the column, it is necessary to provide a device such as 55 the discharging apparatus shown, which will advance the fuel in the peripheral sections of the column at a comparatively rapid rate while at the same time retarding the rate 60 of advancement of material in the axial sections of the column.

To cool the body of coke and ash in the lower portion of the column a water or steam coil 90 is positioned below the cone 72, and has outlets adjacent each of the vertical openings 65 between the peripheral receivers 74 and

the platforms 76 by which water or steam from the waste heat boilers may be directed into the coke and ash to quench and cool it. The agitating action of the revolving cone tends to break up any large bodies in the fuel 70 column into comparatively small pieces and thus provides a porous bed of fuel through which the cooling vapors are distributed throughout the whole cross section of the charge. By means of a heat transfer with 75 this steam the coke is discharged from the bottom of the fuel column in a comparatively cooled state, while the steam reaches the blast zone of the column in a highly preheated state, and enters into reaction with the coke in the high temperature zone, supplementing 80 the action of the moisture in the blast gases introduced from the preheaters.

The coke and ash discharged from the oscillating platforms into the hopper 88 is 85 periodically removed by a revolving cone device 92 at the bottom of the hoppers, which has substantially the same construction as the charging devices 16 used for charging fuel into the top of the shaft, see Figs. 5 90 and 6. The devices 16 are castings in the form of a truncated cone having a hollow cylindrical core 94, and a rectangular slot 96 cut into the wall 98 of the cone. The slot 96 corresponds in length and breadth to the 95 cross-sectional dimensions of the bottom opening of the hopper 10, and likewise of the top of the nostril 20. The housings 18 form connecting links between the hopper bottom and the nostrils 20, and the inner 100 walls 100 of the housings are tapered to conform to the taper of the outer face of the cones 16. A two-piece ring 102 fits into a 105 socket in the face of the large end of the cone 16, forming a flange, and cap screws 104 are used to hold this flange to a face 106 of the housing, in such a way that an airtight bearing surface is provided between the outer wall of the cone and the inner wall of the housing. A number of thin liner bands (not 110 shown) may be preferably placed between the face 106 of the housing and the ring 102, (see Fig. 6) and by removing one or more of these liners at intervals any wear on the core 115 may be taken up. A shaft 108 is fastened to the cone at its center line, and a sprocket wheel 110 is keyed to the shaft. This sprocket wheel is connected to a motor or other 120 source of power, and the cone is by this means caused to revolve in the housing 18. Thus as the cone revolves the slot 96 will pass under the opening in the bottom of the hopper 10, filling the hollow core 94 of the cone with coal. The cone will continue to revolve until 125 the opening of the slot is over the intake nostril 20, when the coal will fall from the cone through the nostril 20 into the charging bell 22 and thence to the generator. The cone revolves continuously, and it will be seen 130 that its construction provides almost a per-

fect seal against the escape of any gases from the generator into the charging hopper. By using this type of mechanism the fuel may be withdrawn from the bottom of the shaft 5 without allowing any gas to escape, and also without having to change the pressures in the generator. The bottom opening of the hopper 88 is offset in order that the vertical shaft 80 may not interfere in any way with 10 the removal of coke from the hopper.

With the use of the apparatus in the manner outlined above, it will be seen that the method of manufacture and quality of gas may be controlled, and that a very good heat 15 balance will be obtained, because heat is utilized with a maximum degree of efficiency. The body of the shaft is clear of obstructions of any kind through out the whole length of the fuel column, and the means provided at 20 the bottom for agitating the charge insures an open column at all times and precludes the formation of any body of plastic material or clinker mass within the shaft. The removal of the central gas offtake and its 25 replacement in the present invention by a peripheral arch offtake with a single nostril increases the actual fuel charging and gas making capacity of the generator not only by an amount corresponding to the volume 30 formerly occupied by the central offtake, but also to a much greater extent by increasing the size of the high temperature zone. This enlarged high temperature zone leads to a greatly increased gas make, which in 35 turn demands an increased rate of passage of fuel through the generator in order to maintain the same grade of gas, and thereby the capacity of the apparatus and resultant efficiency of the process is increased 40 considerably.

The preferred form of the invention having been thus described what is claimed as new is:

1. In gas making apparatus, a gas generating shaft having two vertically spaced nostril openings in its mid-portion, two pre-heaters each having separately controlled interchangeable air and steam inlet and gas offtake connections with the generator 45 through each of said nostril openings, two waste heat steam boilers each having direct blast gas offtake connections with the generator through each of said nostril openings and also having direct gas connections with 50 the pre-heaters, means for conducting steam from said boilers to said pre-heaters, and means for conducting air to the pre-heaters, the said arrangement of apparatus thereby enabling utilization of the sensible heat of 55 the blast gases for generating steam in said boilers and of the potential heat of the blast gases for preheating blast air and for superheating steam in said pre-heaters.

2. In gas making apparatus, an upright 60 gas generating shaft having separately con-

trolled interchangeable vertically spaced circumferential blast inlets and blast gas offtakes in its mid-portion, two preheaters each connected directly with each of the said blast inlets and blast gas offtakes, means positioned 70 in the lower portion of the shaft for agitating and supporting a column of fuel therein, and means cooperating with said fuel supporting means for advancing fuel downwardly at a controlled variable rate through the axial and peripheral portions of said column, respectively, and for discharging the same peripherally of the said fuel supporting means.

3. In gas making apparatus, an upright gas generating shaft having two separately controlled interchangeable gas inlet and blast gas offtake openings in its mid-portion in substantially separated horizontal planes, two preheaters each connected to the shaft through each of said openings, two waste heat boilers each connected directly to the shaft through each of said openings, direct gas connections between the waste heat boilers and the preheaters, and steam connections between the waste heat boilers and the preheaters.

4. In gas making apparatus, an upright gas generating shaft, means for introducing fuel into the top of the shaft, means mounted in the lower portion of the shaft for continuously advancing fuel in a column through the shaft and for removing ash and unburned fuel from the bottom of the column, a circumferential blast inlet in the longitudinal mid-portion of the shaft, a circumferential blast gas offtake in the mid-portion of the shaft vertically separated a substantial distance from the blast inlet, means for rendering said blast inlet and blast gas offtake interchangeable in function, a pair of preheaters each having direct connections with both the said blast inlet and the said blast gas offtake and a rich gas offtake mounted axially in the top of the shaft with its inlet arranged for luting in the upper portion of a column of fuel supported therein.

5. In gas making apparatus, an upright gas generating shaft having separately controlled interchangeable vertically-spaced circumferential blast air inlets and blast gas offtakes in its mid portion, two preheaters respectively directly connected to each of the said blast air inlets and blast gas offtakes, and fuel charging mechanism comprising a hollow truncated cone gate having a rectangular opening on one side, a housing for said cone with a cylindrical tapered inner wall having rectangular openings through opposite sides thereof, means for holding the sides of the cone gate in gas-tight relation to said housing wall, and means for causing said gate to revolve in said housing.

6. In gas making apparatus, a single gas

generating shaft, means for introducing solid fuel at a controlled rate into the shaft, means located in the longitudinal mid-portion of the shaft for selectively introducing a combustion-supporting gas thereto and for removing blast gases peripherally therefrom; means connected with the mid-portion of the said shaft at a point vertically spaced a substantial distance from the last-named means, and adapted for selectively introducing a combustion-supporting gas and for removing blast gases peripherally from the mid-portion of said shaft, separate means in the shaft for removing gas axially from the upper part thereof, rotatable fuel-supporting means in the lower portion of the shaft, means combined with the fuel-supporting means adapted for removing fuel and ash peripherally from the foot of the shaft at a controlled rate, and a steam inlet disposed below the said fuel-removing means, the above combination of means being adapted to facilitate the continuous and regular movement of the fuel and gas vertically through the shaft.

7. Apparatus for heat treating carbonaceous materials containing a volatile portion and a combustible solid portion, comprising a shaft having means for charging and discharging material, means for conducting hot gases from the upper portion of the shaft, a plurality of vertically-spaced means respectively located in the mid-portion of the shaft and adapted for continuously flowing preheated air and superheated steam into the mid-portion of the shaft and for removing gases directly therefrom, a steam generator, valved means connecting the latter selectively with either of the said vertically-spaced means, a plurality of preheaters, valved conduits directly connecting each of the preheaters interchangeably with each of the said vertically-spaced means, conduits directly connecting each of the preheaters with the steam generator, and means for introducing steam into the base of the generator, said last-named means including a water spray device mounted in the lower portion of the shaft in position to quench the hot solid residue of gasification and thereby generate additional steam for gas making.

8. In gas making apparatus, a single gas generating shaft having two vertically spaced nostril openings in its mid-portion, two preheaters, each of the preheaters being in direct controlled communication with the generating shaft through each of the said nostril openings, two waste heat boilers, means establishing direct controlled communication between the generating shaft and each of the waste heat boilers through each of the said nostril openings in the generating shaft, means adapted for directly conducting blast gases from each waste heat boiler to a respective preheater, air inlets at the re-

spective ends of each preheater, and controlled means for directly conducting steam from either boiler selectively to either preheater.

9. In gas making apparatus, a single gas generating shaft having two vertically spaced nostril openings in its mid-portion, two preheaters, each of the preheaters being in direct controlled communication with the generating shaft through each of the said nostril openings, two waste heat boilers, means bypassing the generating shaft and establishing controlled direct communication between each preheater and a respective boiler, air inlets at the respective ends of each preheater, and means for directly conducting steam from either boiler selectively to either preheater.

10. In gas making apparatus, an upright gas generating shaft, an interchangeable circumferential blast air inlet and gas off-take member in the longitudinal mid-portion of the shaft, a second interchangeable circumferential blast air inlet and gas offtake member in the mid-portion of the shaft and vertically spaced from the first-mentioned interchangeable member, means for selectively controlling the admission of air and the withdrawal of blast gases through the respective interchangeable members, whereby a deep high-temperature gas-generating zone is maintained, an eccentrically mounted rotatable device in the lower portion of the shaft adapted for supporting a column of fuel therein, and means associated with the said fuel supporting device for removing carbonized fuel and ash peripherally from the bottom of said column at a controlled rate.

11. In gas making apparatus, a single upright gas-generating shaft having two circumferential vertically-spaced lateral inner wall extensions at about its vertical mid-section, the said shaft having vertically-spaced nostril openings in its walls immediately beneath each of the said wall extensions, means for selectively controlling the admission of air and steam and the withdrawal of blast gases through each of the respective vertically-spaced nostrils whereby a deep high-temperature gas-generating zone is maintained in the mid-portion of the shaft, and a rich gas offtake mounted axially at the top of said shaft.

In testimony whereof I affix my signature.
